UNITED STATES PATENT OFFICE.

ISAAC COOKLIN, OF LIVERPOOL, ENGLAND.

EXTENSIBLE TABLE.

Application filed May 23, 1922. Serial No. 563,137.

To all whom it may concern:

Be it known that I, ISAAC COOKLIN, a subject of the King of England, and residing at Liverpool, in the county of Lancaster, England, have invented Improvements in or Connected with Extensible Tables, of which the following is a specification.

This invention has reference to extensible tables of the kind in which one or more leaves can be automatically moved into position when extending the tables, and also moved out of position and stowed under the table top in contracting the table; and it relates moreover to that type of table where the leaf or leaves is or are brought up from a resting or stowing portion of same, which is constituted by the slide frames of the table, which extends between the two ends; means being employed for moving the two end portions farther from and nearer to each other.

In the table hereinafter described, the improvements under this invention are comprised.

25 In a round or oval table according to this invention, the sliding frames are disposed in lines at points well within the outside edge or sides of the table top, and therefore are relatively close together; and the table 30 top is provided all round with a deep flange or skirting of wood, and the leaf or leaves is or are similarly provided with a deep flange or skirting; and when a leaf is in position the edges of its flanges join up with 35 the edges of the flange or skirting, so that the flange or skirting is continuous when the leaf is in; and the table and parts are so adapted and arranged that when a leaf is removed, and the end parts closed up by the 40 operating screw or means, and the leaf stowed underneath, the two edges of the flange or skirting come together; so that a continuity of this flange or skirting always exists; that is there is never a gap in it.

45 Further in tables of the kind referred to, the edge portions of the leaf are hinged to the central portion of the leaf and so adapted that when the table is opened, these hinged portions will fold—say fall down; and when 50 the leaf passes down below the top, and the table closed up by the operating gear, these hinged edge portions of the leaf will not be visible from the side of the table, they being within the parts of the table connected with 55 permanent ends. In the case of a round or oval table, the foldable parts lie within the

depending flange or skirting portion of the permanent ends of the table, and therefore will be out of sight, and out of the way; and when the leaf is moved into position, 60 and its hinged end parts moved up into position of use, the edges of the flange or skirting will be in line with and engage the edges of the flange or skirting of the table end parts, and so form a continuous flange or skirting; and these leaf end parts, which consist of a short length of the leaf top and the skirting, may be provided with dowels or dowel apertures (the table end top portions being correspondingly furnished) so that when the table is closed after bringing up and inserting a leaf, these hinge or folding end portions will be held in position; and the edges of the leaf flange or skirting may also be grooved and 70 tongued so as to engage with corresponding formation of the edges of the skirtings of the top.

In some cases the hinged end parts of the leaf may be moved automatically into position when the leaf is being inserted in extending the table, and this may be effected by connecting the underside of the leaf by a pivot joint with a bar on the underside of the stationary part or table top, and so arranged that when the table is opened, and the leaf brought up, the jointed ends of the leaf will be moved up into proper position, and vice versa, lowered when the leaf is moved down, and the table closed up.

The invention is illustrated in the annexed drawings in which Figure 1 is a plan with part of the table-top removed or broken away, and Figure 2 is a longitudinal section. Figures 3, 4 and 5 are elevations showing a part of the table to a larger scale; and Figure 6 is a view of a slotted link method of operating the leaves.

The table shown in the drawings is of the character referred to having two removable leaves, and two semi-circular end portions 1, and a central portion 2. The slide frames consist of two sets of outside slides 3 and cross frames 4, attached to the top of each end of the table 1. These frames have no legs attached to them, and are wholly carried by the table top. Between the slides 3 are inner slides 5 attached to the top of the centre portion 2 of the table, connected to and sliding in or on the outer slides 3 by a tongue and groove arrangement in the known way; and the slides 5 are

connected together by cross bars 6, and when the table is closed, with the leaves stowed under the table top, the end bars 6 of the slides 5 come near the end bars 4 of the outer slides 3.

The table tops 1, the centre portion 2 and the leaves 10 all have a deep depending flange or skirting 11 within which the slide frames 3 and 5 lie, the slides being relatively close together, that is, a relatively large distance towards the centre of the table from the skirtings 11; and the legs 12 of the table are all attached to this skirting or flange 11; and as will be seen, one leg is fixed at each of the angles of the inner face or edge of the table-top portions 1, and one is at each angle of the centre portion 2, so that when the table is in its smallest dimension, with both leaves stowed, the legs of the angles of the ends, and those of the centre portion lie close together as shown. At the rounded portion of the ends 1 there are intermediate legs 12 attached to the skirting between those at the angles.

25 A leaf has two bars 16 with an inclined front portion finishing at the front edge, and projecting portions at the other end beyond the other edge of the leaf, which act as weights; and when a leaf is in position in the table, these parts come on the under surface of the table top, and in contact with it; whilst when the leaf is being pulled up from underneath from its stowed position, its inclined ends strike the block 30 17 on the frames 3, 4, or 5, 6, and they are lifted into position level with the table top.

On the leaf there are stops 14 against which projections 15 on the frames 3 come when opening the table, to stow a leaf by 40 the operation of the screw, and pull the dowels at the meeting edges of the leaf and top from one another.

When a leaf is being stowed and one end of the table is being moved away from the 45 other by the screw, the blocks 17 on the slides act on the inclined ends of the bars 16 of the leaf, and cause the leaf to slide back and down under the middle portion 2 of the table top.

50 In the working of the table when the angles at the bottom of the incline of the bars 16 of the leaf reach the top of the incline of the blocks 17, the leaf overbalances from the incline to the horizontal position, the point or angle of the bar 16 being such a distance from the front edge of the leaf as to cause this action.

When the back edge of a leaf is pulled out of the dowels in the top 2 by the parts 60 14, 15 as described, its back end is free to fall, and does fall down, into the bottom of the cut-away slot 18 in the slides 5 in the known way of tables having stowable leaves of the kind concerned.

65 The leaf is moved up into position when

the table is operated, by a slotted link 20, carried and pivoted by a bracket 21 to the table top 1; and it is connected with the bars 16 of the leaf by headed pins 22 fixed to the bars, and passing through the slots 70 23; and these parts are so arranged that when the table portions 1 and 2 are moved away from one another by the operating screw 7 and nut 8 on the cross bar hereinafter described, the leaf is pulled up into position; 75 while when the leaf is to be lowered, it falls into place and is moved into the slots 18 in the known way.

When the pin 22 is first pulled by the link, by the end of the slot coming against the pin, the lower angle of the inclined ends of the bars 16 will just touch the forward end or point of the blocks 17.

The leaf at each end has a foldable part or flap 24, carrying under it a skirting part 11, and it is connected to the body of the leaf by a metal hinge 25 screwed to both parts, the pivot of the hinge being at a point distant from the outer edge of the leaf body, slightly less than the thickness of 90 the leaf; and the outer part 26 of the body on the upper side is shaped to this radius, leaving an upwardly projecting ledge on the body immediately above the hinge axis. The inner edge of the hinge and flap part 24 has 95 a correspondingly curved groove of the same radius, and having the same centre, so that when the flap 24 is up, and in position in the table, the inner upper edge of the flap will lie in contact with the upwardly projecting part of the leaf body above the hinge axis; while when the leaf is stowed in the slots 18 under the table top, the leaf flaps 24 will hang down in position as shown in Figure 3.

When the table is open, and the edges of the top and the leaf leave one another, the flaps 24 are free to fall down about their hinges; but when the leaf is moved into position the flaps 24 are moved into the horizontal position by hand, and held there until the edges of the top and leaf meet, when tongues and grooves 27 on the respective meeting edges of the skirtings 11 meet one another, and engage, so that the flaps 24 are held in position. When the flaps are in this position the skirtings 11 of top and leaf or leaves are continuous round the table.

When the flaps 24 are down they lie within the space between the skirting 11, and the frames 3; and the frames 3, 5, can be spaced apart, about the proportion of the total width of table shown.

In the case of a double leaf table, the movements of the parts are effected by a frame comprising a cross bar 28 (on which the screw nut 8 is fixed) the ends of which slide in grooves in the inside of the inner slides 5, as shown in dotted lines marked 29;

whilst another cross bar 30, connected to it by longitudinal bars 31, is connected to the end slide frames 3 remote from the screw 7. By rotating the screw 7, the outer end 5 of the frame 3 is first moved and the various actions of moving the leaves into an outer position in the table top, and stowing them in the known manner, can be effected, the cross bars on the various frames such as 10 6, 28, and 32 coming in contact with each other to produce the desired effect and movement.

In the case of a table having more than two leaves, the centre portion 2 of the table 15 would be split in two, and a leaf would work in between these two parts.

In some cases, instead of two leaves being operated from one end by a single screw, the two ends in a table and leaves could be 20 worked by a screw from each end of the table; in which case each screw would be supported in a bearing on the inside of the skirting 11, and work in a nut connected with a member of each of the frames 3. And 25 in the case of a single leaf table, the slides of each end would be fixed to the top of the same, and one slide would be within the other similarly as the frames or slides 5 slide in the frame 3; and when such a table 30 has semi-circular ends, the table will be cir-

cular when the leaf is stowed, and the table closed; and these two ends would be similar to the ends of the table shown in the drawing. Also in some cases the slides 3 can extend along the end up to the inside of the 35 skirting 11.

What is claimed is:—

An extension table, including end frames and a central frame carrying table top portions, loose leaves carried between the frames 40 having projections thereon, said central frame having projections to cooperate with the projections on the leaves, links pivotally mounted on the end frames having a limited sliding connection with the adjacent loose 45 leaf, and operating means for relatively moving the frames, whereby the links will move the leaves to cause a cooperation of the projections for raising the leaves into top forming position in one operation of 50 the frames, and the projections will cooperate in a subsequent operation to stow the leaves.

In testimony whereof I have signed my name to this specification in the presence of two subscribing witnesses.

ISAAC COOKLIN.
